UNITED STATES PATENT OFFICE.

CLARENCE RENSHAW, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

SWITCHING APPARATUS.

1,238,336

Specification of Letters Patent. Patented Aug. 28, 1917.

Application filed October 31, 1913. Serial No. 798,483.

To all whom it may concern:

Be it known that I, CLARENCE RENSHAW, a citizen of the United States, and a resident of Edgewood Park, in the county of Allegheny and State of Pennsylvania, have invented a new and useful Improvement in Switching Apparatus, of which the following is a specification.

My invention relates to switching apparatus of the group switch type, and it has special reference to the supporting structure thereof.

The object of my invention is to provide a device of the above indicated character which shall be simple and inexpensive in construction, and particularly adapted to economize vertical space, which is essential for switch groups employed upon certain types of railway cars and locomotives, particularly the well-known "low-floor" cars.

In the prior construction of switch groups, it has been common to provide a supporting frame and to secure the several switch parts directly thereto, insulating them therefrom by suitable bushings and washers. This construction was expensive both in material and in the cost of assembling, and, moreover, occupied unnecessary vertical space.

According to my invention, the structure provided overcomes the difficulties and objections to the prior structures and secures the benefits and advantages hereinbefore mentioned.

In the accompanying drawing, Figure 1 is a view, partially in section and partially in side elevation, of a portion of a switch group constructed in accordance with my invention, and Fig. 2 is a plan view of a portion of said device.

Referring to the drawing, the switch group shown comprises a supporting frame or member 1, having a plurality of large openings 2 disposed in pairs longitudinally and provided with strengthening ribs 3, and an insulating plate or board 4 which is substantially the size of the frame 1 and is secured to its underside by means of a plurality of attaching devices 5 of suitable form.

Beneath the several pairs of openings 2 and in side-by-side relation, a plurality of switching units 6 are suspended in a manner to be hereinafter set forth.

The switch units 6 are of like construction

and each comprises a switch box 7 of insulating material having an open end, a stationary contact terminal 8 and a coöperating movable contact terminal 9. The stationary contact terminal 8 is secured to a block 10 of conducting material which, in turn, is supported from the upper portion 11 of the switch box 7 by means of screws 12. The contact member 9 is movably and resiliently associated with a conducting block 13 by means of an interposed linkage 14, which will not be described. The conducting block 13 is secured to the upper wall 11 of the switch box 7 in a manner similar to that just referred to.

Each of the conducting blocks 10 and 13 is provided with a conducting stud or bolt 15 which has a screw-threaded engagement therewith and which projects through the opening 2 in the frame 1 and through a suitable opening in the insulating board 4. Disposed within the opening 2 and spaced from the sides thereof, is a block or collar 16 of insulating material which surrounds the bolt 15. Such spacing is important in that it materially increases the "creepage distance" between live parts and the frame-work of the switch group. The bolt 15 is provided with a head 17 between which and the insulating collar 16 an external connector 18 and a cross-connecting strip or member 19 are disposed. Thus, the several conducting bolts 15 serve, not only as conducting terminals for the switch parts, but also to clamp the switch parts, together with the switch box, to the insulating plate 4, independently of the supporting frame 1.

Since the upward contact pressure must be withstood by the frame 1 without undue bending, the purpose of the stiffening ribs 3 will be appreciated, although such ribs do not add any unnecessary vertical height to the structure, since the insulating collars 16 are of a corresponding height, but are entirely located within the openings 2. Thus the requisite rigidity and a minimum structural height, as well as good electrical insulating properties, are provided.

I do not wish to be restricted to the specific structural details and the arrangement and location of parts set forth.

I claim as my invention:

1. In a switching device, the combination with a supporting frame having relatively large openings therein, a plate of insulating

material secured to said frame, and a plurality of switch parts severally provided with studs that project through said plate and said openings, of collars of insulating material severally surrounding said studs and disposed in said openings, and spaced from the edges thereof, and means coöperating with said studs and independent of said frame for clamping said switch parts to said plate.

2. In a switching device, the combination with a supporting frame having relatively large openings therein, an insulating plate secured to said frame, and a plurality of switch parts engaging said insulating plate, of a plurality of bolts projecting through said openings and said insulating plate into said switch parts, blocks of insulating material surrounding said bolts within said openings and spaced away from the edges of said openings, and means coöperating with said bolts for clamping said switch parts to said plate independently of said frame.

25 3. In a switch group, the combination

with a supporting frame having a plurality of relatively large openings therein disposed in pairs, an insulating plate covering substantially the whole of the underside of said frame and means for securing said plate to said frame, of a plurality of switching devices disposed beneath said insulating plate and in side-by-side relation and comprising coöperating contact members and conducting members projecting through said frame openings and said insulating plate for securing the relatively movable contact members to said insulating plate independently of said frame, and insulating means disposed within said frame openings and spaced from the edges thereof to provide a relatively long creepage distance between said frame and said conducting members.

In testimony whereof, I have hereunto subscribed my name this 22nd day of Oct., 1913.

CLARENCE RENSHAW.
